UNITED STATES PATENT OFFICE.

PETER BENJAMIN KAMEDISH, OF WINNIPEG, MANITOBA, CANADA, ASSIGNOR OF ONE-THIRD TO SAMUEL THOMAS STARR AND ONE-THIRD TO CHARLES HENRY FORSTER, SR., BOTH OF WINNIPEG, MANITOBA, CANADA.

ATTACHMENT TO LOCOMOTIVE.

Application filed December 10, 1921. Serial No. 521,418.

The invention relates to improvements in attachments to locomotives and the objects of the invention are to provide an automatic drifting attachment for a locomotive that will be put into commission to supply steam for lubricating the engine cylinders instantly upon the closing of the engine throttle and during the time that the engine is drifting and arranged such that it will automatically 5 shut itself off when the engine comes to a stop; to provide a drifting attachment that, when the engine throttle is open, will automatically reset itself for the above-mentioned operation; to provide an attachment 10 constructed so that it will itself be lubricated by exhaust steam admitted from the engine cylinder and so that all condensation can drain therefrom; to construct the appliance such that the steam supplied for lubricating 15 purposes in drifting is directly proportionate to the speed of the drifting engine; to provide a construction which will positively prevent the possibility of an excessively charged engine cylinder due to leakage or 20 other escape of live steam into the cylinder when the throttle is in the closed position and finally to utilize the trapped live steam 25 in the cylinders, valves and steam passages to operate the relief valve when the engine 30 stops.

With the above principal and other minor objects in view, which will become more apparent as the description proceeds, the invention consists essentially in the arrangement and construction of parts hereinafter more particularly described and later pointed out in the appended claims, reference being had to the accompanying drawings in which:—

Fig. 1 is a side view of the forward part of my attachment as applied on a locomotive.

Fig. 2 is an interior view of the cab looking forwardly and showing the parts associated with the throttle lever.

Fig. 3 is a plan view of the parts appearing in Figure 2.

Fig. 4 is an enlarged vertical sectional

view at 4—4' Fig. 3 and looking towards the left.

Fig. 5 is an enlarged detailed vertical sectional view through a number of the various valves employed and parts associated therewith.

Fig. 6 is an enlarged detailed front view 55 of the steam cut-off valve, a portion of the governor cylinder and the air cut-off valve.

Fig. 7 is a vertical sectional view at 7—7' Figure 5.

Fig. 8 is a vertical sectional view at 8—8' 60 Figure 5.

Fig. 9 is a vertical sectional view at 9—9' Figure 5.

Fig. 10 is a vertical sectional view at 10—10' Figure 5.

Fig. 11 is an enlarged detailed longitudinal sectional view through the steam supply valve.

Fig. 12 is a horizontal sectional view at 12—12' Figure 11.

Fig. 13 is an enlarged detailed side view of the air controlling valve located within the cab.

Fig. 14 is a vertical sectional view longitudinally through the air controlling valve, 75 the section being taken at 14—14' Fig. 13.

Fig. 15 is a vertical sectional view at 15—15' Figure 14.

Fig. 16 is a horizontal sectional view at 16—16' Figure 13.

Fig. 17 is a vertical sectional view at 17—17' Fig. 16 and looking in the direction of the applied arrow.

Fig. 18 is a sectional view at 17—17' Fig. 16 and looking in the opposite direction 85 to the applied arrow.

Fig. 19 is a vertical sectional view at 19—19' Figure 16.

Fig. 20 is an enlarged detailed vertical sectional view through the air cut-off valve. 90

Fig. 21 is a vertical sectional view longitudinally through the air controlling valve as it appears in Fig. 14, but with the said valve in the closed position.

Fig. 22 is a view similar to Fig. 6 with 95 the head and associated parts in the position

occupied when they close the lower end of the overlying tube.

Fig. 23 is a vertical sectional view similar to Fig. 16 with the rotary valve changed 5 in position to show the passage 45 connected with the air pressure, and the pipe 28² connected with the exhaust 47.

In the drawings like characters of reference indicate corresponding parts in the several figures.

1 represents the boiler shell of a locomotive, 2 the steam dome, 3 the smoke stack, 4 the smoke box, 5 one of the steam chests containing the valve 6, 7 the dry steam pipe having the rear end connected to the usual superheater header 8 and the forward end connected with the steam chest containing the engine valves.

In this connection I might remark that 20 whilst I have only shown one of the engine valves there is in reality an engine valve at either side of the boiler, such controlling the passage of the live steam to the main steam cylinders. The end of the boiler extends into the cab 9 and within the cab is the usual horizontally disposed pivotally mounted throttle lever 10 to which is connected the throttle rod 11 controlling the passage of live steam from the dome to 25 the stand pipe. The throttle lever is fitted with the customary hand latch 12 and detent 13, the detent operating over a fixed quadrant 14 carried by an angle bracket 15 permanently secured to the end of the boiler. 30 A main reservoir air supply pipe 16 enters the cab.

The above parts are all of ordinary construction and form no part of this invention and for this reason it is considered unnecessary to enter into a more detailed description of the same. In describing my invention I will first refer to the parts in a general way and then describe them in detail.

45 An air controlling valve indicated generally by the reference numeral 18 is permanently mounted on the bracket 15 and presents an operating lever 18' which is connected through an operating link 18² with the throttle lever so that when the throttle lever is shifted the air supply valve is actuated. A steam supply valve 19 is mounted on the dome and is connected by means of a short steam pipe 19' with the interior of the dome and by an air pipe 19² to the air controlling valve 18. A steam cut-off valve 20 is located at the forward side of the boiler and connects through a short pipe 20' with a T-elbow 20² and the elbow is connected by 50 means of the steam pipe 20² with the steam supply valve 19. An intercepting valve 21 is introduced in a steam pipe 22 leading from the steam cut-off valve and connected with the stand pipe. Associated with the 55 intercepting valve I have an intercepting

valve piston 21', the details of which will be later described and in the pipe 22 I introduce a T-elbow 22' which is connected by means of a steam pipe 23' to a double check valve 23. A steam pipe 23² connects the 70 double check valve with the steam chest 5. A steam pipe 23² connects the T-elbow 20² with the double check valve. Adjoining the steam cut-off valve I locate a governing cylinder 24 which controls the movement of the 75 steam cut-off valve lever 25 and directly above the governing cylinder I mount an air cut-off valve 26 which is permanently supported by a bracket 26' carried by the forward end of the steam cut-off valve. This 80 bracket also supports the governor cylinder. The air cut-off valve is inserted in an air pipe 27 leading from the intercepting valve piston 21' to the air controlling valve in the 85 cab. A further air pipe 28 leads from the intercepting valve piston 21' to the air controlling valve 18 within the cab. A steam pipe 29 connects the stand pipe with the governing cylinder 24 and an escape pipe 30 leads from the steam pipe 20² to the smoke 90 stack.

The air controlling valve 18 herein before referred to embodies in its construction a slide valve 31 and a rotary valve 32. The slide valve 31 operates in an air chamber 33 95 and is carried by a slidably mounted valve rod 31' suitably mounted in bearings provided at the ends of the valve chamber, it being observed that the ends of the rod project beyond the bearings. One face of the 100 valve is provided with a spanning valve slot 31² and the valve is adapted to operate over an exhaust port 34 and a port 35 connecting the pipe 19² with the air chamber 33. The arrangement of the valve is such that when shifted in one direction it opens the port 35 and when shifted in the other direction connects the port with the exhaust port 34.

The rear end of the pipe 28 is fitted with a T-elbow 28' and branches at the elbow and one of the branches indicated at 28² communicates with the chamber 33 whilst the other branch 28² connects with the rotary valve casing 36 hereinafter more fully described.

110 The air controlling valve is supported from the bracket 15 by a two-armed bracket 37 and these arms support comparatively small cylinders 38 and 39 which contain pistons 40 and 41, the pistons being provided with extending stems 40' and 41' respectively 115 which are axially aligned with the valve rod 31' and have their inner ends butting the ends of the said rod.

120 The pipe 27 herein before mentioned communicates with the cylinder 39, the arrangement being such that air admitted by way of the pipe 27 acts on the piston 41 and moves it in a direction which will shift the slide valve to the left (see Figure 14.) An auxil- 125

iary air reservoir pipe 17 connects with an auxiliary air reservoir provided and is fitted with a T-elbow 17' and branches at the elbow, one branch 17² connecting with the outer end of the cylinder 38 whilst the other branch 17^x communicates with the rotary valve casing as later described.

The construction is such that air when applied from the pipe 16 through the air supply valve 18 to the pipe 17² operates to shift the piston 40 to the right and bring it and the slide valve to the position shown in Fig. 14 and also fills the auxiliary air reservoir through the pipe 17. An emergency lever 15 42 is attached to the valve rod to permit the rod to be operated by hand in event of the boiler steam pressure becoming too low due to some defect in the locomotive.

The bracket 37 supports the rotary valve 20 casing 36 which is located directly beneath the slide valve chamber. This casing contains the rotary valve 32 herein before mentioned, said rotary valve being attached in any suitable manner to the valve shaft 43 and rotating therewith. To the valve shaft the lever 18' is secured.

In the present instance the outer face of the rotary valve is shown as supplied with a rib 32' slidably received within a complementary groove 43' formed in a head 43^x located at the inner end and formed as part of the shaft 43. An air distributing chamber 36' is reserved in the rotary valve casing at the front of the valve and it communicates directly with the main reservoir air supply pipe 16. The valve is supplied at diametrically opposite points with an air port 44^a passing completely therethrough and a facial radially disposed slot 44^b and 40 with a further set of diametrically opposing through slots or ports 44^c and 44^d which are shifted in advance of the former port and slot and are of considerable length and made concentric to the axis of the valve. 45 The slot 44^d goes completely through the valve, whilst the slot 44^c only goes partially through the same.

In the normal or closed position of the throttle lever, which it will be observed is 50 directly connected by the operating link 18² to the valve lever 18', the slot 44^b is adapted to connect through a passage 45 in the back of the casing the branch pipe 17^x with an exhaust opening 45' provided in the wall of 55 the valve casing and the branch 28² of the pipe 28 is adapted to be connected through a passage 46 provided in the casing with the port 44^a of the valve. In the shifted position of the throttle lever the exhaust opening 45' is cut off by the slot 44^b passing away from it and the passage 45 is brought into communication with the distributing chamber 36' through the slot 44^d, and the port 44^a is cut off and the branch pipe 28² is 60 brought directly into communication with an

exhaust passage 47 in the casing through the slot 44^c.

According to the above arrangement it will be obvious that this distributing valve provides a means directly controlled by the manipulation of the throttle lever for admitting compressed air from the main air reservoir pipe alternately to either the branch pipe 17^x or the branch pipe 28² and for exhausting alternately from these pipes. 75

It is here explained also that when the throttle is closed the pipes 17² and 17 both exhaust through the air valve by way of the passage 45. This comparatively large volume of exhausting air slows down the rate 80 of exhaust from the cylinder 38 so that the slide valve cannot shift under the pressure of the air in the pipe 27 until the valve 63, later mentioned, has seated.

The steam supply valve 19 comprises an air cylinder 48 communicating with the pipe 19² connected to the valve 18 and containing a piston 49 operating in the cylinder and carried by a slidably mounted spindle 49', the end of which projects into the valve casing 90 50 and carries the steam valve 51 operating on the valve seat 51'. The valve is normally held seated by the pressure of the boiler steam and remains so till disturbed by the pressure of the air acting on the piston 49, 95 which action is later described. When the valve 51 is closed steam cannot pass from the dome to the pipe 20^x. Obviously if air be admitted to the cylinder 48 the piston therein would be shifted to the left as in Figure 100 11 and the valve 51 will be opened and held open to permit the free passage of live steam from the dome to the pipe 20^x. The steam cut-off valve 20 is now described in detail. It comprises a cylindrical casing 52 having one side closed and the other side open and communicating with the short pipe 20' and the lower part thereof connecting directly with the pipe 22 herein before referred to. Within the casing I place a stationary cylindrical shell 53 fitted with a plurality of diametrically opposing slots or steam passages 53', the shell forming with the casing an annular chamber 54 which opens the pipe 22. Within the shell I mount rotatably a cylindrical valve 55 having the stem 55' thereof passing rotatably through the closed end of the casing and carrying the lever 25. The valve 55 is formed with a plurality of equi-spaced longitudinally extending steam 115 56 which are in direct communication through the open end of the casing with the short pipe 20' and consequently the pipe 20^x, and slot like ports 56' are formed in the face of the valve, such being designed to be brought into and out of registration with the steam passages 53' in the manipulation of the valve 55.

According to the above description it will be apparent that when the latter valve is 130

closed, that is when the ports and steam passages are out of registration, there will be no direct passage of steam from the pipe 20^x to the pipe 22 and that when the valve is open the steam can freely pass from the pipe 20^x to pipe 22 by way of the annular chamber 54. Provision is made so that one can adjust the lever 25 on the spindle 55' but as the details of this are of little consequence I have not 10 considered it necessary to describe them herein.

The governor cylinder 24 contains a piston 57 provided with a vertically disposed stem 58 which extends through the upper end 15 of the cylinder and terminates in a circumferentially slotted exterior head 59, the slot of the head receiving a pin 60 extending from the free end of the lever 25. A spring 61 is mounted on the stem 58 and acts to 20 force down the piston 57. It will here be observed that the pipe 29 leads from the bottom end of the governor cylinder to the dry pipe so that the piston 57 is directly under 25 the influence of the pressure of the steam in the dry pipe.

The air cut-off valve 26 which is interposed in the pipe 27 presents a valve seat 62 crossing the interior of the valve casing and it contains a vertically slideable valve 63 held 30 normally seated on the seat by a pressure spring 64 located above the valve. A hollow or tubular stem 65 passes downwardly slidably through the said valve casing, the lower 35 end of the tube communicating under certain conditions with atmosphere and under other conditions being closed by the head 59 of the stem 58. At the upper end of the stem there is an escape opening 66 which in the closed position of the valve connects the rear-going 40 part of the pipe 27 with the open centre of the stem in which position it is shown in Figure 20. By referring to this figure it will be obvious that when the air cut-off 45 valve 26 unseats there is a through connection by way of the air cut-off valve between the intercepting valve cylinder 21 and the interior of the cylinder 39 but here I wish to point out that at this time the lower end of the tubular stem 65 is closed by contact with 50 the head 59. Further, I might mention that when the valve 63 is seated any air in the end of the pipe 27 leading to the cylinder 39 can exhaust by way of the opening 66 and through the lower end of the tubular stem 55 as the head 59 in the lowering of the piston 57 passes away from the stem 65.

The double check valve 23 comprises a casing 67 having one side communicating with the pipe 23^x, the other side connecting with 60 the pipe 23' and the bottom opening to the pipe 23^x. Within the casing I locate a stationary sleeve 68 which forms with the casing an interior annular chamber 69. The sleeve is supplied with a plurality of equi-spaced slots 68' which form connections be-

tween the interior of the sleeve and the chamber. Within the sleeve I locate what might be termed a double check valve comprising an outer valve 70 slidably mounted in the sleeve and an inner valve 71 carried by the outer valve. The outer valve is provided with a circumferential channel 68^x adapted to register with the slots 68' and at equi-spaced intervals I form facial slots 68^x 70 in the outer valve which form escape passages between the channel 68^x and the pipe 23^x. The valve 71 is adapted to close against the valve seat 72 provided on the outer valve and the stem 71' of the inner valve projects through the outer valve, a clearance space 80 being reserved to permit of the passage of steam when the inner valve is open. It is explained that the small check valve 71 is provided to permit the exhaust steam, when the throttle is open, to flow past it to the pipe 23^x and parts connected therewith, thereby lubricating such parts and keeping the same 85 from freezing in cold weather. The stem of the valve 71 is fitted with a pin 72^x which prevents the said valve from closing the passage to the pipe 23^x when both the valve 70 and 71 are shifted to the left under the pressure of the entrapped steam as later explained.

The intercepting valve 21 which is interposed in the pipe 22 below the steam cut off valve presents an interior vertically disposed dividing valve seat 73 which presents a central circular valve opening 74 which slidably receives the cylindrical skirt 75' of the valve 75. It will be observed that the diameter of the said valve is somewhat less than the interior diameter of the casing so that an annular escape passage 76 is reserved between the outer edge of the valve and the casing 100 when the said valve is open. The skirt of the valve is provided with a plurality of slots 77.

The stem 78 of the valve 75 is slidably mounted in the side of the casing and has 110 the end projected therebeyond and fitted with a head 79 adapted to make a steam tight joint in the cylinder 80 later described.

The intercepting valve 21 comprises a cylinder 80 associated with the intercepting 115 valve and within the latter cylinder an air operating piston 81 is slidably mounted, which piston is adapted under the pressure of the air from the pipe 28 to move to the left and hold the valve 75 unseated during the interval the locomotive is drifting and during the interval the locomotive is standing still with the throttle closed. When the valve 75 closes, the stem thereof shifts the piston 81 to the right thereby resetting it. Any leakage past the stem 78 or piston 81 is 120 free to escape through the opening 82 when the head is unseated.

The above completes the description of the parts but in order that the invention may be 130

more thoroughly understood I will now describe the manner in which it operates, assuming initially that the locomotive is working, that is to say it is running under steam, and latterly that the throttle is closed and that the locomotive is drifting.

In the working condition of the locomotive the throttle is open and live steam is being supplied in the usual manner through the dry pipe 7 to the main engine valves and cylinders. The valve 51 is closed and there is no live steam in the pipe 20^x. Air is also being admitted from the main air supply pipe 16 to the chamber 36' and through the port 44^a and passage 45, to the branch pipe 17^x with the result that the auxiliary air reservoir (not shown) is charged through the pipe 17 and the cylinder 38 is charged through the branch pipe 17². The intercepting valve is held closed by the pressure of the steam in the main steam passages of the engine. The piston 57 of the governor cylinder is up, being held up by the pressure of the live steam passing through the pipe 29 from the dry steam pipe 7, and consequently the head 59 is engaged with, closes, and holds up the hollow stem 65, such resulting in the valve 63 being held open. In the working condition of the locomotive, the pressure of the exhaust steam from the cylinders will force the valve 71 of the double check valve open so that exhaust steam can get by to lubricate and heat the parts. At this time however, the valve 63 is inactive as there is no air pressure in the air pipes 27 and 28, such pipe being open to atmosphere.

As the air in the pipe 27 has escaped past the open valve 63 and through the air passage 80^x provided by longitudinally slotting the outer end of the cylinder 80, into the pipe 28 and from the pipe 28 and pipe 22² to the port 46 where it reaches the slot 44^c which is in direct communication with the exhaust passage 47. Due also to the lever connection between the governor cylinder and the steam cut-off valve, the lever being at this time up, the steam cut-off valve is practically closed, just sufficient passage or leakage being permitted to allow exhaust steam to work back up through the pipes 23², 23' and 23^x the valve 20 and pipes 20² and 20^x to escape pipe 30. This lubricates the parts and prevents freezing in winter time.

The above are the existing conditions when the throttle is open. On closing the throttle, that is upon pushing it forwardly to its limit the locomotive comes to the drifting position and the following operations occur.

The closing movement of the throttle lever operates the rotary valve 32 through the link 18² and lever 18' and brings the said rotary valve into the position as shown best in Figures 16, 17 and 18 which is the

closed position of the valve. The air from 65 the main air supply pipe 16 passes through the port 44^a to the pipe 28 and through this pipe to the intercepting valve piston but at this time does not move the piston 81 to the left (see Fig. 5) as the air pressure is 70 not high enough to overcome the steam pressure against the valve 75 which is at this time closed. Simultaneously the air passes through the branch pipe 28^x past the slide valve 31 to the pipe 19² through which it 75 passes to the steam supply valve 19 where it acts on the piston 49 which it forces over to open the steam valve 51. When this occurs live steam passes through the pipe 20^x to the elbow 20² where it branches and 80 passes through the short pipe 20' to the steam cut-off valve 20 and through the pipe 23^x to the double check valve 23. The closing of the throttle causes a quick drop in the pressure of the steam in the dry pipe 7 85 and this releases through the pipe 29 the piston 57 which is forced down by the action of the spring 61. As the piston 57 drops the head 59 moves down and effects through the lever 25 the turning of the 90 valve 55 to fully open position, thereby permitting of the passage of steam from the dome directly through the steam cut-off valve to the pipes 22 and 23.

As the head 59 moves down the valve 63 is 95 seated by the spring 64 and cuts off air pressure to the pipe 27 and allows whatever pressure is in the pipe 27 to exhaust through the opening 66 and stem 65. This prevents any air pressure being in the pipe 27 which would 100 move the valve 31 to the position which would allow the valve 19 to close and consequently shut off drifting steam during the drifting period. Prior, however, to the opening of the valve 55 the pressure in the dry 105 pipe 7 quickly reduces the controlling back pressure on the face of the valve 75 by way of the opening 76 with the result that the valve 75 opens under the action of the previously built up pressure in the pipe 22 and 110 the air pressure acting on the piston 81. It is here explained that the pressure built up in the pipe 22 is due to leakage space permitted past the valve 55. The valve 75 accordingly opens without having to wait, 115 so to speak, until the pressure in the dry pipe has dropped quite low due to the movement of the engine pistons. Upon the steam cut-off valve 20 and the intercepting valve 21 being both open drifting steam is 120 supplied directly from the dome through the pipe 20^x and the pipe 22 to the dry pipe and to the engine valves and cylinders. There is also a quantity of steam passing by way of the pipe 30 to the smoke stack which aids in raising and reducing black smoke. 125 Steam also branches into the pipe 23^x and reaching the double check valve 23 shifts

the same to the right and positively cuts off any passage of steam through the pipe 23' to the pipe 22. When the double check valve 71 is closed a small amount of steam 5 is permitted to pass through the slots 68^x, channels 68^z and slots 68' to the pipe 23^z and into the exhaust passage of the engine. This latter steam prevents the action of the engine pistons from pulling hot smoke box 10 gases into the cylinders while drifting, which obviously would be injurious to the lubricant. The arrangement provided also supplies drifting steam in direct proportion to the speed of the engine. This is brought 15 about in the following way.

As the piston displacement becomes gradually less due to the decrease of speed, steam pressure gradually builds up in the dry pipe 7 and reacts through the pipe 29 on the 20 piston 57 of the governor cylinder, raising it. In connection with the building up of the steam pressure in the dry pipe it is explained that the pipe 20^x is designed to supply steam to the engine cylinders in sufficient 25 quantities such that for all drifting speeds of the engine said engine will exhaust less steam than such supply through the said pipe 20^x and on this account there will be a gradual building up of the steam in the 30 dry pipe during the drifting period. The gradual rising of the said piston swings the arm 25 upwardly and gradually closes the valve 55, the closing of such valve being in direct proportion to the gradual rise of the 35 steam pressure in the stand pipe, this latter being due to the gradual decrease of piston displacement. Should the engine be shut off at slow speed and due to drifting down-hill for instance, the piston displacement 40 becomes greater, pressure under piston 57 would drop, resulting in the gradual opening of the valve 55.

When the engine comes to a stop or the 45 engine pistons are inert there is a quick building up of steam pressure in the pipe 22 and the dry pipe 7, such being due to the leakage of steam allowed past the valve 55 which has not been fully closed. Upon this 50 steam pressure becoming stronger than the combined pressure of the air at and on top of the air cut-off valve 26 and its spring, the piston 57 rises further and lifts the air cut-off valve 63 from its seat 62, thereby permitting air to pass freely through the pipe 55 55 27 and reach the air controlling valve 18 at the cylinder 39. Here the air which is from the main reservoir pushes the piston 41 inwardly and brings the slide valve 31 into a position such that the pipe 19^z is spanned 60 by the slot 31^x and can exhaust to atmosphere through the port 34. As soon as the pipe 19^z exhausts the steam pressure acts on the steam area of the valve 51 to seat the valve 51 and shut off the live steam supply from

the dome to the pipe 20^x. The steam remaining in the pipe 20^x after the latter valve is closed escapes through the pipe 30 to the smoke stack as well as through the pipe 23^x, double check valve 23, and pipe 23^z to the 65 70 exhaust passages.

I wish here to explain that when the air pressure acts on the piston 41 as above described there is only atmospheric pressure in the branch pipe 17^z for the reason that when the throttle was initially closed the ports 45 and 45' were spanned by the slot 44^b and the pipe 17^x which communicates with that 17^z is accordingly open to atmosphere and the air pressure behind the piston 40 and in the auxiliary reservoir 17 will be 75 80 atmospheric, having escaped through the ports 45 and 45'.

Reverting now to the conditions subsequent to the engine coming to a stop. After the engine has stopped and steam has been shut off at the valve 51 there is steam trapped between the steam cut-off valve 20 and the engine pistons. The steam escaping from the pipe 20^x through the pipe 30 to the stack reduces the pressure in the pipe 23^x and permits the large volume of live steam trapped between the steam cut-off valve and engine pistons to act on the double check valve and open it quickly to allow the 90 95 said trapped steam to escape freely through the pipe 23^z to the exhaust passages. Here it is explained that the pressure of the trapped steam shifts the outer valve 70 to the left and opens the slots 68' as well as opens the valve 71 thereby allowing the 100 105 trapped steam to quickly escape, a small quantity thereof going past the valve 71 to the pipes 23^x, 20^x and 30 and to the stack and the major part thereof going through the slots 68' of the valve 70 to the pipe 23^z 110 where it escapes through the exhaust passages. It is further explained that when the engine is drifting, the live steam pressure in pipes 20^x, 20^z and 23^x operates to close the valve 71 and shift the valve 70 to the right far enough to partially open the slots 68' and thereby permits sufficient live steam to pass through the pipe 23^z to the 115 exhaust passages in order to stop the back suction in the cylinders which is brought about by the fact that the engine is drifting. Further, the closing of the valve 70 prevents live steam getting into the pipe 23^z and interfering with the volume of the steam admitted to the pipe 22 by way of the valve 20. 120

The valve 75 remains open during the drifting period, also when stopping and when the engine is still, during which time the throttle is obviously closed. As soon as the engine is started by opening the throttle the ports 46 and 47 are bridged by the slot 44^c which allows the air pressure in the 125

pipe 28 to exhaust and consequently the valve 75 will shift to the closed position under the pressure of the steam in the pipe 22.

What I claim as my invention is:

- 5 1. In a drifting attachment to locomotives, the combination with the locomotive cylinders, the throttle and the live steam pipe leading to the cylinders from the throttle, of a steam supply valve in direct communication with the boiler, means for unseating the valve coincident with the closing of the throttle, a normally closed steam cut-off valve connected with the steam supply valve, a double check valve, a pipe connection between the double check valve and the steam cut-off valve, a steam pipe connection between the double check valve and the cylinder exhaust passages, a steam pipe connection between the double check valve and the live steam pipe, a pipe connection between the steam cut-off valve and the live steam pipe, and means whereby a reduction of pressure in the live steam pipe effects the opening of the steam cut-off valve. 70

10 15 20 25 30 35 40 45 50 55 60 65 70 75 80 85 90 95 100 105 110 115 120 125 130 135

2. In a drifting attachment to locomotives, the combination with the locomotive cylinders, the throttle and the live steam pipe leading to the cylinders from the throttle, of a steam supply valve in direct communication with the boiler of the locomotive, means for unseating the valve coincident with the closing of the throttle, a normally closed steam cut-off valve directly connected with the steam supply valve, a pressure operated double check valve directly connected with the steam cut-off valve and with the live steam pipe, a steam pipe connection between the double check valve and the cylinder exhaust passages, a pipe connection between the steam cut-off valve and the live steam pipe and means to open the steam cut-off valve upon a reduction of pressure occurring in the live steam pipe. 95

3. In a drifting attachment to locomotives, the combination with the locomotive cylinders, the throttle and the live steam pipe leading to the cylinders from the throttle, of a steam supply valve in direct communication with the boiler, means for unseating the valve coincident with the closing of the throttle, a normally closed steam cut-off valve, a governor cylinder, an operating connection between the governor cylinder and the steam cut-off valve, a steam pipe connection between the steam cut-off valve and the steam supply valve, a pressure operated double check valve, a steam pipe connection between the steam cut-off valve and the double-check valve, a steam pipe connection between the double check valve and the live steam pipe, a steam pipe connection between the double check valve and the cylinder exhaust passages, and a steam pipe connection between the governor cylinder and the live steam pipe. 110

4. In a drifting attachment to locomotives, the combination with the locomotive cylinders, the throttle and the live steam pipe leading to the cylinder from the throttle, of a steam supply valve in direct communication with the boiler, means for unseating the valve coincident with the closing of the throttle, a normally closed steam cut-off valve, a governor cylinder, an operating connection between the governor cylinder and the steam cut-off valve, a steam pipe connection between the steam cut-off valve and the steam supply valve, a pressure operated double check valve, a steam pipe connection between the double check valve and the live steam pipe, a steam pipe connection between the double check valve and the cylinder exhaust passages and a steam pipe connection between the governor cylinder and the live steam pipe whereby a reduction in the pressure of the steam in the live steam pipe effects the opening of the steam cut-off valve. 115

5. In a drifting attachment to locomotives, the combination with the locomotive cylinders, the live steam pipe leading to the cylinders, the throttle and a service air pipe, of a normally closed steam supply valve in direct communication with the boiler, an air controlling valve connected with the air service pipe and with the steam supply valve, a connection between the air controlling valve and the throttle whereby air is admitted through the air controlling valve to the steam supply valve coincident with the closing of the throttle, means associated with the steam supply valve whereby the admitted air unseats the steam supply valve, a normally closed steam cut-off valve, a governor cylinder, an operating connection between the governor cylinder and the steam supply valve, a steam pipe connection between the steam cut-off valve and the steam supply valve, a pressure operated double check valve, a steam pipe connection between the double check valve and the steam cut-off valve, a steam pipe connection between the double check valve and the live steam pipe, a steam pipe connection between the double check valve and the cylinder exhaust passages and a steam pipe connection between the governor cylinder and the live steam pipe whereby a reduction in the pressure of the steam in the live steam pipe effects the opening of the steam cut-off valve. 120

6. In a drifting attachment to locomotives, the combination with the locomotive 125

cylinders, the throttle and the live steam pipe leading to the cylinders from the throttle, of a steam supply valve in direct communication with the boiler, means for unseating the valve coincident with the closing of the throttle, a normally closed steam cut-off valve, a steam pipe connection between the steam supply valve and the steam cut-off valve, a steam pipe connection between the

latter steam pipe and the cylinder exhaust ¹⁰ passages, a steam pipe connection between the steam cut-off valve and the live steam pipe and means whereby a reduction of pressure in the live steam pipe effects the opening of the steam cut-off valve. ¹⁵

Signed at Winnipeg, this 1st day of November, 1921.

PETER BENJAMIN KAMEDISH.
